US0D1109642S

(12) **United States Design Patent** (10) **Patent No.:** **US D1,109,642 S**
(45) **Date of Patent:** **** Jan. 20, 2026**

(54) **VEHICLE**

(71) Applicant: **VOLVO CAR CORPORATION**, Gothenburg (SE)

(72) Inventor: **Haoran Zhang**, Gothenburg (SE)

(73) Assignee: **VOLVO CAR CORPORATION**, Gothenburg (SE)

(**) Term: **15 Years**

(21) Appl. No.: **29/933,771**

(22) Filed: **Mar. 21, 2024**

(30) **Foreign Application Priority Data**

Sep. 28, 2023 (EM) 015035519-0001

(51) **LOC (15) Cl.** **12-08**

(52) **U.S. Cl.**
USPC **D12/86**

(58) **Field of Classification Search**
USPC D12/86, 88, 90, 91, 92; D21/433, 434,
D21/533, 535
CPC B62D 25/00; B62D 25/06; B62D 33/00;
B62D 35/00

See application file for complete search history.
